TRUNK LOCK

Harry A. Cooper, Stamford, Conn., assignor to
 The Yale & Towne Manufacturing Company,
 Stamford, Conn., a corporation of Connecticut

Application January 16, 1947, Serial No. 722,360

17 Claims. (Cl. 70—75)

1

This invention relates to a lock and more particularly to that type of lock used for locking trunks.

The usual trunk lock comprises a hasp that is pivoted to one part of the trunk and is adapted to interlock with another part of the trunk through the medium of locking mechanism carried by the hasp. Generally, but not necessarily, this locking mechanism comprises a bolt or bolts movable relatively to the hasp by a key controlled mechanism, there being provided on the other part of the trunk, usually the cover, a cup-shaped strike into which the bolts may enter. Those skilled in the art will recognize that the particular combination outlined is well known and used very widely.

It has become customary in the trunk art to secure the locking mechanism to the hasp through means of rivets, and then to hinge the hasp relatively to a hinge support that is itself riveted. Not only is this riveting relatively expensive, but it is not pleasing to the eye and renders the lock subject to attack, as the rivets may be filed away and otherwise removed. It is the object of my invention to contribute a trunk lock of the hasp type in which rivets will be eliminated so that the hasp will present an outer smooth streamlined surface appearance such as is highly desirable in the art. It is a further object of my invention to mount the hasp in position, and to secure to the hasp the locking mechanism, in a simple and most effective manner.

I have thus outlined the general nature of my invention and its relation to the prior art in order that the description thereof that follows may be better understood, and in order that my contribution to the art may be better appreciated. There are, of course, additional features of my invention that will be described hereinafter and which will form the subject of the claims appended hereto. Those skilled in the art will appreciate that the conception on which my disclosure is based, may readily be utilized as the basis for the designing of other structures for carrying out the several purposes of my invention, and that my claims should not be limited to the structure herein shown and described.

Referring now to the drawings, Fig. 1 is a perspective view of the hasp of my invention. Fig. 2 is a section taken along lines 2—2 of Fig. 1. Fig. 3 is a perspective view of the underside of the hasp and illustrating the lock assembly removed therefrom and in exploded relation thereto. Fig. 4 is a section taken along lines 4—4 of

5 5—5 of Fig. 2.

Referring now more particularly to the drawings, the hasp of my invention is indicated generally by reference numeral 10, and in the preferred form of my invention, it is formed of sheet metal. By suitably bending the sheet metal, flanges 11 are formed at the sides of the hasp, while by suitable cutting and bending, one end of the hasp is shaped into a curved flange or lip 12. Prior to this bending of the flanges, a hole 13 is formed through the face of the hasp, and grooves 14 in the metal forming the side flanges 11.

The forming of these grooves 14 is probably best illustrated in Fig. 5. Thus, a shearing tool is driven into the metal, bending it as shown in dotted lines at 14a in Fig. 5, this bending resulting from the shaping of the groove 14, and forming what is in effect a protuberance. Thereafter, the protuberance at 14a is eliminated by grinding and polishing. Therefore, a smooth outer surface remains on each of the flanges 11, while on the inside surfaces of the flanges four shallow grooves 14 are present for the purposes to be indicated hereinafter. It will be well to add at this point that the grooves 14 will be slightly inclined vertically relatively to the flanges 11 for a purpose to be indicated below.

30 A locking assembly for the hasp is designated generally by reference letter L, and here comprises a cup-shaped member 15 formed of sheet metal and having openings 16 for a pair of latch-bolts 17. Through an integral flange 18, the cup-shaped member 15 is secured by rivets 19 to what I term a mounting plate 20. Mounted within the cup-shaped member 15 is a suitable key plug 21 rotating relatively to a neck 22 forming part of the lock assembly and extending from the mechanism within the cup-shaped member 15. Those skilled in the art will appreciate that everything in the locking assembly is well known in the art, and is not per se my invention. However, it should be emphasized that the mounting plate 20 is not conventional, and is assembled to the locking assembly to form a part thereof and thereby effecting its functioning as part of the novel combination of this invention.

40 The mounting plate 20 is formed with integral downwardly bent lugs 23 as best seen in Fig. 2, these lugs being adapted to rest on the inner surface 10a of the face of the hasp 10 and to maintain the locking assembly in proper position. The plate 20 is further formed with an upwardly bent flange 24 having curved lugs 25 at each end

thereof so bent as to lie initially as shown best in Fig. 5 in dotted lines, whereby not to interfere with the placing of the lock assembly between the flanges 11 of the hasp.

With the lugs 25 bent as shown in dotted lines in Fig. 5 and as shown in full lines in Fig. 3, the locking assembly L is moved in position between the two flanges 11 until the neck 22 snaps into the hole 13 while one end of the mounting plate 20 and a part of the flange 18 of the cup-shaped member 15 lie under the curved lip 12 at one end of the hasp. At this point, the two lugs 25 are bent from their dotted line position of Fig. 5 into their full line position and into the grooves 14. Because the grooves 14 are inclined as earlier set forth, the movement of the lugs 25 therein, serves to draw the locking assembly 17 downwardly and firmly into position through coaction of the lugs 25 with the inclined groove walls. It is now obvious that the locking assembly will be fully and completely secured to the hasp 10. It will be appreciated that while this securing is full, complete and very adequate for the particular purpose, no rivets or other fastening means are required.

Referring now to the left end of the hasp 10 as seen in Fig. 3, it will be noted that the metal 28 integral with the metal of the front of the said hasp is slotted at 30 and then curled about a hinge pin 31 best seen in Fig. 2, and then downwardly against the inner face 10a of the hasp 10. The ends of the sheet metal 28 thus lying against the inner surface 10a of the hasp are bent upwardly at 32, with the outer ends 33 in the form of lugs similar to the lugs 25 and similarly bent so that the sheet metal 28 may move into the position illustrated in Fig. 3 with the lugs 33 not preventing such movement. Thereafter, the lugs 33 are moved into the slots 14 in the same manner that the lugs 25 are moved into their slots 14. Now the hinge pin 31 is in proper position and supported relatively to the hasp.

The hinge pin is carried by a hinge support plate 34 which through a bore 35 is bolted to the trunk body by means that need not here be shown. With the hinge support plate 34 secured to a trunk, the hasp may now pivot relatively to the trunk about the hinge pin 31, with the locking assembly moving into and out of locking relation to the usual strike found on trunks of the particular class.

I believe that the merits of my invention, its construction and operation, will now be apparent to those skilled in the art.

I now claim:

1. In a lock of the class described, a hasp formed of sheet metal to present a front face and with the sheet metal cut and bent to form integral lateral flanges at both sides and at one end, a part of the end flange being bent inwardly to form a retaining lip, and said side flanges each having a shallow groove, a locking assembly comprising a rotatable key plug, a cylinder in which said key plug rotates, and a bolt mounted for movement relatively to the cylinder and retracted by rotation of said key plug, said hasp having an opening in its front face through which the key plug of said locking assembly is accessible when said locking assembly is applied to the back surface of said front face and between the side flanges and the end flanges, a part of said locking assembly lying under the retaining lip of the end flange, and lugs on said locking assembly extending into said shallow grooves.

2. In a lock of the class described, a hasp

formed of sheet metal to present a front face and with the sheet metal cut and bent to form integral lateral flanges at both sides and at one end, a part of the end flange being bent inwardly to form a retaining lip, and said side flanges each having a shallow groove, a locking assembly including a rotating key plug, said hasp having an opening in its front face through which the key plug of said locking assembly is accessible when said locking assembly is applied to the back surface of said front face and between the side flanges and the end flanges, a part of said locking assembly lying under the retaining lip of the end flange, and lugs on said locking assembly extending into said shallow grooves.

3. In a lock of the class described, a hasp having a front face and laterally extending integral flanges at both sides and at one end thereof, a locking assembly comprising a rotatable key plug, a cylinder in which said key plug rotates, and a bolt mounted for movement relatively to the cylinder and retracted by rotation of said key plug, said hasp having an opening in its front face through which the key plug of said locking assembly is accessible when said locking assembly is applied to the back surface of said front face and between the side flanges and the end flanges, a part of said locking assembly lying under the retaining lip of the end flange, and lugs on said locking assembly movable into a retaining groove formed in at least one of the other flanges.

4. In a lock of the class described, a base member having a front face and laterally extending integral flanges at both sides and at one end thereof, a locking assembly, a part of one of said lateral flanges bent inwardly to overlie a part of said locking assembly, and lugs on said locking assembly initially positioned and shaped to allow the locking assembly to move into position between the other flanges, said lugs being adapted for bending to move into retaining grooves formed in the said flanges.

5. In a lock of the class described, a hasp having a front face and laterally extending integral flanges at both sides and at one end thereof, a locking assembly comprising a rotatable key plug, a cylinder in which said key plug rotates, and a bolt mounted for movement relatively to the cylinder and retracted by rotation of said key plug, said hasp having an opening in its front face through which the key plug of said locking assembly is accessible when said locking assembly is applied to the back surface of said front face and between the side flanges and the end flanges, a part of the end flange of said hasp bent inwardly in retaining relation to said locking assembly when said locking assembly is pushed into place with a part thereof under said end flange, and lugs coacting between said two side flanges and said locking assembly adapted to be bent into retaining grooves to retain the said locking assembly against movement from under the end flange.

6. In a lock of the class described, a hasp having a front face and laterally extending integral flanges at both sides and at one end thereof, a locking assembly comprising a rotatable key plug, a cylinder in which said key plug rotates, and a bolt mounted for movement relatively to the cylinder and retracted by rotation of said key plug, said hasp having an opening in its front face through which the key plug of said locking assembly is accessible when said locking assembly is applied to the back surface of said front

face and between the said three flanges, a part of the end flange of said hasp bent inwardly in retaining relation to said locking assembly when said locking assembly is pushed into place with a part thereof under said end flange, and lugs on said locking assembly initially positioned and shaped to allow said locking assembly to move into position between said side flanges and with part thereof under said end flange, said lugs being adapted for bending into retaining grooves formed in the side flanges to secure said locking assembly in position.

7. In a lock of the class described, a hasp having a front face and laterally extending integral flanges at both sides and at one end thereof, a locking assembly comprising a rotatable key plug, a cylinder in which said key plug rotates, and a bolt mounted for movement relatively to the cylinder and retracted by rotation of said key plug, said hasp having an opening in its front face through which the key plug of said locking assembly is accessible when said locking assembly is applied to the back surface of said front face and between the said three flanges, a part of the end flange of said hasp bent inwardly in retaining relation to said locking assembly when said locking assembly is pushed into place with a part thereof under said end flange, and lugs on said locking assembly initially positioned and shaped to allow said locking assembly to move into position between said side flanges and with part thereof under said end flange, said lugs being adapted for bending into retaining grooves formed in the side flanges, said grooves being narrow and formed parallel to the front face of said hasp and tapering from the surfaces of the side flanges to a shallow depth, while inclined vertically to coact with the lugs to force the locking assembly against the back surface of the hasp.

8. In a lock of the class described, a hasp formed of sheet metal to present a front face and with the sheet metal cut and bent to form integral lateral flanges at both sides and at one end, a part of the end flange being bent inwardly to form a retaining lip, and the inside surfaces of said side flanges each having a shallow groove tapering from the surface thereof, a locking assembly comprising a rotatable key plug, a cylinder in which said key plug rotates, and a bolt mounted for movement relatively to the cylinder and retracted by rotation of said key plug, said hasp having an opening in its front face through which the key plug of said locking assembly is accessible when said locking assembly is applied to the back surface of said front face and between the side flanges and the end flange, a part of said locking assembly lying under the retaining lip of the end flange, and lugs on said locking assembly extending into said shallow grooves.

9. In a lock of the class described, a hasp formed of sheet metal to present a front face and with the sheet metal cut and bent to form integral lateral flanges at both sides and at one end, a part of the end flange being bent inwardly to form a retaining lip, and the inside surfaces of said side flanges each having a groove, a locking assembly comprising a rotatable key plug, a cylinder in which said key plug rotates, and a bolt mounted for movement relatively to the cylinder and retracted by rotation of said key plug, said hasp having an opening in its front face through which the key plug of said locking assembly is accessible when said locking assembly is applied to the back surface of said front face

and between the side flanges and the end flanges, a mounting plate to which said locking assembly is secured to be so applied to said hasp, said mounting plate underlying the retaining lip of the end flange, and lugs on said mounting plate extending into said grooves.

10. In a lock of the class described, a hasp formed of sheet metal to present a front face and with the sheet metal cut and bent to form integral lateral flanges at both sides and at one end, a part of the end flange being curled inwardly to form a retaining lip for a hinge pin, the inside surfaces of said flanges each having a shallow groove tapering from the surfaces thereof, and lugs on said retaining lip extending into said shallow grooves to hold said hinge pin retaining lip in retaining position.

11. In a lock of the class described, a hasp formed of sheet metal to present a front face and with the sheet metal cut and bent to form integral lateral flanges at both sides and at one end, a part of the end flange being curled inwardly to form a retaining lip for a hinge pin, the inside surface of said flanges each having a shallow groove, and lugs on said retaining lip extending into said shallow grooves to hold said hinge pin retaining lip in retaining position.

12. In a lock of the class described, a hasp formed of sheet metal to present a front face and with the sheet metal cut and bent to form integral lateral flanges at both sides, one end of said hasp having an extension bent downwardly from the front face and against the inside surface of said front face to form a support for a hinge pin, the inside surfaces of said side flanges each having a groove, and lugs on said extension extending into said grooves to hold said extension in hinge pin support position.

13. In a lock of the class described, a hasp having a front face and laterally extending integral flanges at both sides and at one end thereof, a locking assembly comprising a rotatable key plug, a cylinder in which said key plug rotates, and a bolt mounted for movement relatively to the cylinder and retracted by rotation of said key plug, said hasp having an opening in its front face into which extends the end of the cylinder and through which the key plug of said locking assembly is accessible when said locking assembly is applied to the back surface of said front face and between the said three flanges, a part of the end flange of said hasp bent inwardly in retaining relation to said locking assembly when said locking assembly is pushed into place with a part thereof under said end flange, and lugs coacting between said two side flanges and said locking assembly adapted to be bent into retaining grooves to retain the said locking assembly against movement from under the end flange.

14. In a combination of the class described, a base member having a front face and laterally extending integral flanges at both sides thereof, an assembly adapted to be secured to said base member in a position between said flanges, the inside surfaces of said flanges having retaining grooves formed therein, and lugs on said assembly initially shaped and positioned to allow said assembly to be placed between said flanges, said lugs being adapted for bending thereafter into said grooves in said flanges to secure said assembly to said base member.

15. In a combination of the class described, a base member having a front face and laterally extending integral flanges at both sides and at one end thereof, an assembly adapted to be se-

cured to said base member between said flanges, a part of said end flange bent inwardly to overlie a part of said assembly, and lugs on said assembly initially positioned and shaped to allow the assembly to move into position between the side flanges, said lugs being adapted for bending thereafter into retaining grooves formed in the inner surfaces of said side flanges whereby to secure said assembly to said base member.

16. In a combination of the class described, a hinging base formed of sheet metal and with the sheet metal cut and bent to form integral lateral flanges at both sides and at one end, a part of the end flange being curled inwardly to form a retaining lip for a hinge pin, the inside surfaces of said side flanges each having a groove therein, and lugs on said retaining lip initially shaped and positioned to allow said retaining lip to move into position between said side flanges, said lugs being movable thereafter into said grooves to hold said hinge pin retaining lip in retaining position.

17. In a combination of the class described, a hinging base having a front face and integral lateral flanges at both sides, one end of said hinging base having an extension bent downwardly from the front face and against the inside surface of said front face to form a support for a hinge pin, the inside surfaces of said side flanges each having a groove, and lugs on said extension extending into said grooves to hold said extension in hinge pin support position.
